UNITED STATES PATENT OFFICE.

ALFRED LEE VINYARD, OF SLIDELL, LOUISIANA.

RAIL-JOINT.

SPECIFICATION forming part of Letters Patent No. 748,672, dated January 5, 1904.

Application filed May 8, 1903. Serial No. 156,170. (No model.)

To all whom it may concern:

Be it known that I, ALFRED LEE VINYARD, a citizen of the United States, residing at Slidell, in the parish of St. Tammany and State of Louisiana, have invented certain new and useful Improvements in Rail-Joints; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in rail-joints, and has for its object to provide a simple and efficient device for holding together the meeting ends of adjacent sections of rails.

A further object is to provide an improved combined fish-plate and rail-chair.

With this and other objects in view the invention comprises an arrangement and combination of parts hereinafter described and claimed.

In the accompanying drawings, Figure 1 is a perspective view of one part of my device. Fig. 2 is a similar view of the other part. Fig. 3 is an end elevation showing the rail in section. Fig. 4 is a horizontal section on the line 4-4 of Fig. 3 with the rail removed.

My invention comprises fish-plates 6 and 7, each of which has a base-plate 6^a and 7^a, respectively, which overlap under the base of the rail and form a chair therefor. Both base-plates have extensions 6^b and 7^b, respectively, having holes 6^c and 7^c to receive the spikes. The joint between the parts is formed by tongues and grooves in the respective parts. The base-plate 6^a, which is the under plate, has inclined tongues 8, extending diagonally across the line of the rails, and the upper

base-plate 7^a has grooves 9, which receive said tongues. By this construction the fish-plates are interlocked when the parts are assembled, and lateral and longitudinal displacement is prevented. The base-plate 7^a overlaps the base-plate 6^a, and the latter has spike-holes 6^d, which register with the spike-holes 7^c in the former. When the spikes are driven through these registering holes, the parts will be securely held against separation. The fish-plates proper have bolt-holes 9^a for the usual horizontal bolts 10, which pass through the web of the rail.

In use the fish-plates are first interlocked and spiked to the sleepers. The rails are then inserted endwise therebetween and secured by the bolts 10.

Having thus described my invention, what is claimed as new, and desired to be secured by Letters Patent, is—

1. A rail-joint comprising fish-plates having overlapping base-plates provided with inclined interlocking tongues and grooves and extending under the base of the rail, and registering spike-holes through the base-plates, substantially as described.

2. A rail-joint comprising fish-plates having overlapping base-plates extending under the base of the rail, one of said base-plates having inclined grooves, and the other having inclined tongues fitting the grooves for interlocking the base-plates, and extensions on each side of the base-plates having registering spike-holes on one side, substantially as described.

In testimony whereof I affix my signature in presence of two witnesses.

ALFRED LEE VINYARD.
